UNITED STATES PATENT OFFICE.

ALBERT J. SAYERS AND JOHN H. D. PETERSEN, OF CHICAGO, ILLINOIS, ASSIGNORS TO
LINK-BELT COMPANY, A CORPORATION OF ILLINOIS.

AUTOMATIC HUTCH DEVICE FOR JIGS AND THE LIKE.

1,202,901.

Specification of Letters Patent.

Patented Oct. 31, 1916.

Application filed April 22, 1915, Serial No. 23,048. Renewed September 5, 1916. Serial No. 118,547.

To all whom it may concern:

Be it known that we, ALBERT J. SAYERS and JOHN H. D. PETERSEN, citizens of the United States, residing at Chicago, in the county of Cook and State of Illinois, have invented a certain new and useful Improvement in Automatic Hutch Devices for Jigs and the like, of which the following is a specification.

10 Our invention relates to an automatic hutch for jigs.

It relates particularly to means for automatically and, periodically freeing the jig chamber from the accumulated fines.

15 It is illustrated in the accompanying drawings somewhat diagrammatically and with modifications.

Figure 1 is a cross section of a jig to which our invention has been applied; Fig. 2 is a section on the line 2-2 of Fig. 1; Fig. 3 is a section on the line 3-3 of Fig. 2; Fig. 4 is a section on the line 4-4 of Fig. 1; Fig. 5 is a section on the line 5-5 of Fig. 4; Fig. 6 is a section on the line 6-6 of Fig. 4 with valve removed. Fig. 7 is a section through a modified form.

Like parts are indicated by the same letter in all the figures.

A, A is a housing or tank divided up into 30 three chambers A¹, B, B. These chambers have inclined bottoms A² located in the housing. B, B are plunger chambers in which move the plungers B¹, B¹ suspended from vertical rods B², B² which depend from 35 the reciprocating eccentrically mounted heads B³, B³ on the shafts B⁴, B⁴ which are mounted on the standards B⁵, B⁵ supporting the casing and its interior walls B⁶, B⁶ which form the plunger chambers. From 40 each of the heads B³ projects a lug C to which is pivotally attached the link C¹, the other end of which is pivotally attached to one end of the arm C², the other end of which is pivoted on the shaft C³. Said arm 45 carries a pawl C⁴ adapted to engage the teeth of the ratchet wheel C⁵ also mounted on the shaft C³ and integral with or attached to the beveled gear C⁶. D is another beveled gear at right angles to the beveled gear 50 C⁶ in mesh with it and mounted upon the vertical shaft D¹. All these parts are suitably mounted and held in operative position upon a frame consisting of the bed plate D², the standards D³, D³ and the bearings D⁴, D⁴. Each shaft D¹ passes down-

wardly and to its lower end is fastened a valve which consists of the separated side straps E, E and the bottom E¹ containing the radially disposed apertures E². This valve is received within the non-rotatable part E³ and rests upon a valve seat E⁴, being properly centered therein by the downwardly projecting part E⁵ on the valve which seats in a corresponding recess in the valve seat. The valve seat is provided with openings E⁶ somewhat similar in shape to the openings E², E² in the valve. Obviously as the valve rotates it will cause the two sets of openings to register and thus provide an outlet from the lower part of the jig tank 60 and the valve will be caused to rotate by the movement of the eccentrically mounted head B³.

In order that the effective area of the outlet may be adjustable we provide an adjusting ring F beneath the valve seat. It is provided with the openings F¹, F¹ and a square lug F² whereby it may be rotated on its axis. The valve seat and ring are all contained within a centering plug G properly positioned and fixed in the bottom of the casing and beneath the tank.

It will be understood that the parts are so shaped that the fines will be brought as indicated at J, J into a proper position 85 above the valve in the bottom part of the tank.

In the modified form of the valve we provide at the bottom of the tank a valve seat K into which fits a plug valve K¹ on a stem 90 K², and this stem is attached at K³ to a lever K⁴ pivoted at K⁵ and adapted at its other end to be engaged by some moving part which will intermittently raise the valve. The valve rod or stem D¹ or K² may 95 be housed in a tubular housing D⁵ or in the partition B⁶, or if the partition is not required and a housing is, it may take the form illustrated in Fig. 7.

It will be understood that we do not wish 100 to be limited to the particular size, proportion and arrangement of the several parts here illustrated and that my drawings are to be taken as in an important sense diagrammatic, as great changes could be made in 105 these particulars departing from the spirit of our invention.

The use and operation of our invention are as follows: The jiggling operation in the particular form of jig here illustrated con- 110

sists in forcing the water through the plunger chambers up through the jiggling screens and the separation is effected and the material delivered in any desired manner according to the type of jig from above such screens. A certain amount of so-called fines consisting either of the material to be saved, or refuse, or both, escapes through the screen and descends into the jig tank. This material must, of course, be carried away and various devices for that purpose have been from time to time utilized. An operator may open a valve or discharge opening from time to time or a steady stream of water may be permitted to flow or such fines may be discharged into a side projection of the main tank and be thence removed by conveyers. It is desirable that there should be the least possible waste of water and frequent discharges of the fines. According to the method utilized in our invention the fines are intermittently discharged with comparative frequency in relatively small masses with a minimum of water by the weight of the water above. To put it in another way, we deliver a series of charges of fines intermittently. Any desired means for thus operating the valves intermittently may be employed, but we have shown one, and, of course, that or any like means is applicable to any kind of jig. The parts should be constructed or set so as to properly time the action, and in like manner it is desirable to properly regulate the outlet. These adjustments will be determined by the nature and quantity of the material dealt with. The rotation of the driving shaft will properly reciprocate the plungers so as to effect the desired separation. The rotation of the same shaft will rotate the valves step by step, leaving the discharge open for a relatively short space of time during each revolution of the valve. The frequency of the valve rotation may, of course be adjusted by varying the point of connection between the rod C and arm C¹ and the area of the outlets may be varied by rotating the adjusting

plate by means of a wrench or handle. By effecting either or both of these adjustments from time to time the requirements of any given case may be met and there will be a series of relatively quick discharges of the accumulated material, the same passing out in a sort of charge by the action of the weight of the water above it. 50 55

We claim:

1. A discharge valve for jigs and the like comprising a sleeve, an annular stepped flange on the inside thereof, a perforate shutter plate resting upon and positioned by said flange and means for rotating it, a perforate valve seat resting upon said shutter plate and said flange and contained within said sleeve, an annular collar carried by and projecting upwardly from the valve seat, an apertured valve disk resting upon said seat contained inside the annular collar and having its perforations in operative relation to the perforations in the seat and the shutter. 60 65

2. A discharge valve for jigs and the like comprising a sleeve, an annular stepped flange on the inside thereof, a perforate shutter plate resting upon and positioned by said flanges and means for rotating it, a perforate valve seat resting upon said shutter plate and said flange and contained within said sleeve, an annular collar carried by and projecting upwardly from the valve seat, an apertured valve disk resting upon the seat 70 75 80 contained inside the annular collar and having its perforations in operative relation to the perforations in the seat and the shutter, a valve stem, open connections between the stem and the outside of the valve disk, and means for rotating the stem to operate the valve. 85

Signed at Chicago, Illinois, this 19th day of April, 1915.

ALBERT J. SAYERS.
JOHN H. D. PETERSEN.
